UNITED STATES PATENT OFFICE.

FRANCIS H. RICHARDS, OF HARTFORD, CONNECTICUT.

DESIGN FOR A MACHINE-FRAME.

SPECIFICATION forming part of Design No. 19,745, dated April 1, 1890.

Application filed February 28, 1890. Serial No. 342,151. Term of patent 14 years.

To all whom it may concern:

Be it known that I, FRANCIS H. RICHARDS, a citizen of the United States, residing at Hartford, in the county of Hartford and State of Connecticut, have invented and produced a new and original Design for Machine-Frames, of which the following is a specification, reference being had to the accompanying drawing, forming part thereof.

10 In the drawing the machine-frame embodying my design is shown in side elevation, and the design shown is especially intended for the frames of grain-weighing machines.

15 The leading feature of my design consists in the figure G, mounted on a column B and set over one side of the column, and having the curved figure D extending outwardly and downwardly. A further feature relates to the

ornamentation of the design by the dividing-band F at the top of the column and the 20 broadened base H at the lower end thereof. The column B is shown formed symmetrical to a central line a a and joins the broadened base H by the large curves e e, thus making a neat and handsome outline. 25

Having thus described my design, I claim—

The design for a machine-frame herein shown and described, the same consisting in the figure C, mounted on a column and set over one side of said column and having the 30 figure D downwardly projecting, as set forth.

FRANCIS H. RICHARDS.
